ELECTRON TUBE CONTROLLED RELAY
CIRCUIT

Paul N. Martin, Penn Township, Allegheny County, Pa., assignor to The Union Switch & Signal Company, Swissvale, Pa., a corporation of Pennsylvania

Application September 30, 1948, Serial No. 51,925

5 Claims. (Cl. 175—320)

1

My invention relates to electron tube circuits, and particularly to means for checking the proper operation of such circuits when associated with circuits the improper failure of which would create a dangerous condition if not checked.

It has previously been proposed to provide block signaling systems for railways in which four indications are secured by the use of full-wave alternating current or half-wave rectified current of opposite polarities applied to the exit end of the track circuits of the systems at various times in accordance with traffic conditions. At the entrance end of the track circuits direct current track relays with associated rectifiers are provided and arranged so that one of the relays will be picked up by half-wave rectified current of one polarity and the other relay will be picked up by half-wave rectified current of the opposite polarity, and both relays will be picked up by full-wave alternating current.

However, a system arranged in this manner is subject to unsafe failures if a rectifier associated with the track circuit equipment becomes short-circuited, or open-circuited, or a combination of both.

It is well-known in the art that an electron tube and an associated relay may be substituted for a track relay and such a substitution may be readily made in the system of the type described, but such an arrangement is subject to similar defects as described above for systems employing relays only.

Accordingly, it is an object of my invention to provide means for checking the response of an electron tube circuit to a control voltage of a distinctive type.

Another object of my invention is to provide electron tube circuits in which failures of a portion of the circuits will not result in an unsafe operation of the equipment associated therewith.

A further object of my invention is to provide electron tube circuits which respond only to half-wave rectified current of a predetermined polarity.

A further object of my invention is to provide a railway signaling system employing electron tube circuits, the proper operation of which is continuously checked.

Other objects of my invention and features of novelty therein will be apparent from the following description taken in connection with the accompanying drawing.

In practicing my invention I provide a first electron tube circuit including a relay and an alternating current source and which is ar-

2

ranged so that when control energy of the proper polarity and phase relationship with respect to the alternating current source is supplied to a grid of the tube, the tube will conduct and thus energize the relay. In order to check that the relay associated with the first electron tube circuit is energized only when control energy of a distinctive character is supplied to the first electron tube circuit, I provide a second electron tube circuit including a relay and a source of alternating current energy which is opposite in phase relationship to the source provided for the first circuit. The control energy supplied to the grid of the first tube is also supplied to the grid of the second tube. The tube associated with the second circuit is arranged to become conductive when the instantaneous polarity of the energy supplied to its anode is positive with respect to the cathode provided the grid of the second tube then has a zero potential or a positive potential with respect to its cathode. Accordingly, the relay associated with the second electron tube circuit will pick up only when half-wave rectified energy is supplied thereto which is effective to render the first electron tube conductive, but will not pick up on the supply of full-wave alternating current energy to the control grid of the first and second electron tube or on the supply of half-wave rectified energy of the polarity which is not effective to render the first tube conductive.

I shall describe one form of apparatus embodying my invention and shall then point out the novel features thereof in claims.

The accompanying drawing is a diagrammatic view showing the circuits of a three-block, four-indication railway signaling system employing electron tube circuits embodying my invention.

It is to be understood that my invention is not limited to use with electron tube circuits in railway signaling systems and this one illustration will serve to illustrate the many places in which my invention is useful.

Referring to the drawing, there is shown a stretch of railway track over which traffic normally moves in the direction indicated by an arrow and which track is formed by the usual insulated rail joints 1 into successive sections of a signal system and of which sections only the full section 2T and the adjoining ends of the adjacent sections 1T and 3T are shown because these are sufficient for a full understanding of my invention.

It is to be understood that the equipment, not shown, for sections 1T and 3T and the other

sections is similar to that associated with section 2T.

Each of the sections is provided with a signal for governing movements of traffic into the section, such as signal 2S, which governs the movement of traffic entering section 2T. The signal may be of any of the well-known types and is here shown as a two unit color light signal, the top unit having a green lamp 2AG, a yellow lamp 2AY, and a red lamp 2AR, and the bottom unit having a green lamp 2BG and red lamp 2BR.

The apparatus associated with each signal includes two relays, 2ATR and 2BTR, each having associated therewith a gas filled electron tube VA and VB of the well-known thyratron type and an anode supply transformer 2AT and 2BT, respectively, and a checking relay 2CTR governed by a gas filled electron tube VC of the thyratron type.

A power transformer 2PT is provided for supplying energy to the relays 2ATR, 2BTR, and 2CTR, and to the gas tubes associated therewith, a primary winding of transformer 2PT being supplied with alternating current energy from line wires L1 and L2 which constitute a power line extending the length of the stretch and which are connected to a suitable source of alternating current energy, not shown.

The lamps of each signal are supplied with energy from a secondary winding of a lighting transformer 2LT, the primary winding of which is connected to the power line wires L1 and L2. The supply of energy to the lamps of the signal is governed by contacts of relay 2ATR and 2BTR to provide different aspects in accordance with traffic conditions in advance of signal 2S.

The gas tubes as here shown are of the form in which at least one of the grids is provided with two terminals and between which terminals the grid element is connected in series.

The gas tubes VA, VB, and VC are governed by energy supplied thereto from a coupling impedance or load resistor R1 which is connected across the rails at the entrance end of section 2T and is supplied with energy fed over the track rails 5 and 6 from the exit end of the section.

The apparatus at the exit end of the section comprises a track transformer 2TT, a half-wave rectifier K1, and circuits for supplying energy to the rails 5 and 6 which include contacts of relays 3ATR and 3BTR. The relays 3ATR and 3BTR are similar in their operation to the relays 2ATR and 2BTR and are governed by traffic conditions in section 3T and sections in advance of section 3T.

It is believed that the description of my invention will be facilitated by describing the operation of the system as a train moves through the various sections.

The apparatus is shown in its normal or clear traffic condition, that is, with no train occupying section 2T and at least two sections in advance thereof.

Under normal conditions, half-wave rectified energy of what I shall call negative polarity is supplied to the rails 5 and 6 at the entrance end of the section 2T, and is supplied to the load resistor R1 connected across the rails at the entrance end of the section by a circuit which is traced from the left-hand terminal of the secondary winding of transformer 2TT, over rail 6, to the lower terminal of load resistor R1 and through the load resistor R1 and over rail 5 to the exit end of the section, over back contact 9

of relay 3ATR, over front contact 11 of relay 3BTR, through the rectifier K1, over front contact 13 of relay 3BTR, and over back contact 15 of relay 3ATR to the other terminal of the secondary winding of transformer 2TT.

The instantaneous polarity of the various portions of the circuit and the associated apparatus during one-half of the supply energy under normal conditions are designated by plus and minus signs in the drawing, and at the entrance end of the section, it will be seen that the lower terminal of the load resistor R1 is positive with respect to the upper terminal during this half cycle. The cathode 17 of tube VB is connected to the upper terminal of resistor R1, and additionally connected to the lower terminal of a secondary winding 19 of transformer 2PT, while the upper terminal of secondary winding 19 is connected in series with the shield grid 21 of tube VB and the primary winding 23 of the anode transformer 2BT, and thence to an adjustable tap 25 of resistor R1. It will be seen that at this time the current supplied to the shield grid 21 of the tube VB flows from the lower terminal of the transformer secondary winding 19, to the upper terminal of the load resistor R1, through the load resistor R1 to tap 25, through the primary winding 23 of transformer 2BT from the uppermost terminal to the lowermost terminal, and through the shield grid 21 of tube VB to the negative terminal of secondary winding 19 of transformer 2PT. The anode 27 of tube VB is supplied with energy by a circuit which may be traced from the top terminal of the secondary winding 29 of transformer 2BT through the winding of relay 2BTR, a front contact 31 of relay 2CTR closed in a manner to later appear, and which is connected in multiple with a front contact 33 of relay 2ATR, the anode 27 and the tube space to the cathode 17 of tube VB and to the lower terminal of secondary winding 29 of transformer 2BT. This particular arrangement for supplying the shield grid voltage and the anode energy to the tube VB is fully shown and described in my copending application for Letters Patent of the United States, Serial No. 545,519, filed on July 18, 1944. It is deemed sufficient to point out that the circuit for supplying energy to the shield grid 21 is a series circuit which includes the shield grid 21, the secondary winding 19 of transformer 2PT, the load resistor R1, and the primary winding 23 of the anode transformer 2BT. Accordingly, an interruption of any portion of the shield grid circuit will cause the supply of energy to the primary winding 23 of transformer 2BT to be cut off, with the result that the energy supplied from the secondary winding 29 of transformer 2BT to the anode circuit of the tube VB including the winding of relay 2BTR will be cut off, so that the tube VB cannot be fired and relay 2BTR cannot be picked up if the voltage applied to the shield grid 21 is lost.

The control grid 35 of tube VB is connected to the resistor R1 at the adjustable tap 25 by a circuit which includes in series therewith the limiting resistors R2 and R3 and the control grid 37 of tube VC, so that the energy supplied to the control grid 35 of tube VB must also be supplied to the control grid 37 of tube VC, since both are in series. The cathode 39 of tube VC as well as the shield grid 41 of tube VC are connected to the upper terminal of resistor R1, as is the cathode 17 of tube VB.

Again the shield grid 47 of tube VA is included in a series circuit that extends from the lower

terminal of secondary winding 81 of transformer 2PT through shield grid 41, primary winding 83 of anode transformer 2AT, adjustable terminal 51 to the lower terminal of resistor R1 and to the upper terminal of secondary winding 81.

It follows that during this half cycle of the source of supply the track circuit current flows from the lower to the upper terminal of resistor R1. Consequently, the adjustable terminal 25 is of a positive voltage with respect to the upper terminal of resistor R1. Accordingly, the control grid 35 of tube VB and the control grid 37 of tube VC are both positive with respect to their cathodes. At this time the anode 27 of tube VB is additionally positive with respect to the cathode 17, so that the tube VB is rendered conductive, and the energy which flows through the winding of relay 2BTR causes the relay to pick up its contacts. The anode 43 of tube VC is supplied with energy from the secondary winding 45 of transformer 2PT, which has its upper terminal connected to the anode 43 of tube VC through the winding of relay 2CTR, while the lower terminal is connected to the cathode 39 and the shield grid 41 of tube VC. With instantaneous polarities as shown, the cathode 39 and the shield grid 41 of tube VC are positive with respect to the anode 43, so that the tube is not conductive.

However, during the next half cycle of the alternating current supply voltage under normal conditions, the instantaneous polarities as shown on the drawing are reversed, and current cannot flow through the rectifier K1 at the exit end of the section, so that no energy is supplied to the resistor R1 from the track circuit. Also the energy now supplied to the anode 27 of tube VB is negative in potential with respect to the cathode 17 and tube VB is non-conductive regardless of any voltages that may be applied to the control and shield grids of the tube. The relay 2BTR is arranged and proportioned to have a slow enough releasing time to bridge the alternate half cycles in which the tube is non-conductive, and the relay remains picked up under clear traffic conditions.

With the instantaneous polarities reversed from those shown on the drawing, it will be seen that the polarity of the energy supplied to the anode circuit of tube VC is such as to cause the tube to conduct, since at this time there is substantially no control voltage supplied to the control grid 37, and additionally, the shield grid 41 being connected to the cathode has the same potential as the cathode, so that it does not prevent conduction of the tube. Accordingly, the relay 2CTR will be energized during this half cycle, and its front contacts will be picked up, contact 31 of relay 2CTR being closed in the anode circuit of tube VB, to complete the circuit for supplying energy to the winding of relay 2BTR. The relay 2CTR is also arranged and proportioned to be slightly slow in releasing its contacts so that its contacts remain picked up during the alternate half cycles in which the tube VC is non-conductive.

The shield grids of the tubes VA and VB are arranged and connected so that a negative voltage with respect to the cathode is supplied to the shield grid during the time that the anode is positive. As a result, the control grid must have a positive potential at least as great as a given value supplied thereto in order for the tube to fire at this time. Tube VC has its shield grid connected to its cathode, so that the tube VC

can fire each time its anode is positive, even if no positive control voltage is supplied to the control grid.

From the foregoing, it will be seen that under normal or clear traffic conditions, the apparatus at the entrance end of section 2T is supplied with track circuit current comprising pulses of half-wave rectified energy of negative polarity and the tubes VB and VC are alternately rendered conductive, and as a result of the relays 2BTR and 2CTR are picked up.

Turning now to the tube VA with its associated relay 2ATR under the normal condition, it will be seen that when the instantaneous polarities are those shown on the drawing, the polarity of the energy supplied from the secondary winding 51 of transformer 2AT is such that the anode 53 of tube VA is negative with respect to the cathode 49, so that the tube does not conduct and its associated relay 2ATR is deenergized. This shield grid 47 of tube VA is positive with respect to the cathode 49 at this time, but does not influence the action of the tube. Additionally, it will be seen that the cathode 49 of tube VA is connected to the lower terminal of resistor R1, while the control grid 55 of tube VA is connected through a limiting resistor R5 to an adjustable tap 57 of resistor R1. Since at this time the lower terminal of resistor R1 is positive with respect to the upper terminal, it will be apparent that the cathode 49 of tube VA is positive with respect to the control grid 55 of the tube, so that the tube is additionally prevented from conducting due to the negative voltage supplied to its grid. During the other half cycle of the supply energy under normal conditions, the anode 53 of tube VA is positive with respect to cathode 49, but the shield grid 47 is negative in potential with respect to cathode 49 and no control voltage is applied to control grid 55 and the tube VA is retained non-conductive.

From the foregoing, it will be seen that under clear traffic conditions, that is, with section 2T unoccupied and the relays 3ATR and 3BTR in the positions shown, the relays 2BTR and 2CTR will be energized and their contacts will be picked up, while the contacts of relay 2ATR will be released.

A circuit for supplying energy to the upper green lamp 2AG of signal 2S is established over a back contact 59 of relay 2ATR and a front contact 61 of relay 2BTR, while the lower red lamp 2BR of signal 2S is supplied with energy by a circuit including front contact 63 of relay 2BTR. The signal 2S therefore displays an aspect of green over red, denoting "proceed."

It will now be assumed that a train moving from left to right passes the signal 2S and enters section 2T. The wheels and axles of the train 60 shunt the energy supplied over the rails 5 and 6 from the exit end of section 2T, so that track circuit current voltage is no longer developed across the load resistor R1 at the entrance end of the circuit, and as a result, the supply of positive control voltage to the grid 37 of tube VC and grid 35 of tube VB is cut off during the half cycle in which the anode 27 of tube VB is positive. As previously explained, the shield grid 21 is made negative in potential with respect to the cathode 17 by the energy from secondary winding 19 during the half cycle in which the control grid 35 is made positive due to the track circuit current and consequently the tube VB no longer conducts when the section 2T is occupied and the voltage to grid 35 is cut off.

It is to be observed that tube VC is conductive during alternate half cycles of the supply energy the same as before and relay 2CTR is retained picked up while the train occupies the section 2T. Again tube VA is non-conductive when the section 2T is occupied since its shield grid 47 is negative in potential with respect to cathode 49 and substantially no control voltage is applied to control grid 55 during the half cycle in which the anode 53 is positive with respect to the cathode 49. Thus relay 2ATR remains released with section 2T occupied.

After a short time interval the contacts of relay 2BTR will release, and when contacts 61 and 63 of relay 2BTR release a circuit is established for supplying energy to the upper red lamp 2AR of signal 2S over back contact 59 of relay 2ATR and back contact 61 of relay 2BTR, and energy is supplied to the lower red lamp 2BR of signal 2S, over back contact 59 of relay 2ATR and back contact 63 of 2BTR, so that the signal displays an aspect of red over red, denoting "stop."

When the train enters section 3T, relay 3BTR will release in the same manner that relay 2BTR is released when the train entered section 2T. With relay 3BTR released its contacts interrupt the supply of half-wave rectified energy of negative polarity to the rails of section 2T and establish the supply of full-wave alternating current energy to the rails of section 2T. If desired, a limiting resistor may be placed in one of the leads to the track rails to limit the current which flows thereto from track transformer 2TT during the time that the track section 2T is occupied by a train.

When the rear of the train vacates section 2T, full-wave alternating current energy is supplied from the exit end of the section over the rails 5 and 6 to the load resistor R1 connected across the rails at the entrance end of the section. This circuit may be traced from the terminal of the secondary winding of transformer 2TT designated by the plus sign, over rail 6, to the lower terminal of resistor R1, the resistor R1 and over rail 5 to back contact 9 of relay 3ATR, over back contact 11 of relay 3BTR, and over back contact 65 of relay 3ATR to the other terminal of the secondary winding of transformer 2TT.

As previously described, tube VB will be rendered conductive when the lower terminal of resistor R1 is positive with respect to the upper terminal. During the other half cycle of the track circuit current and the upper terminal of resistor R1 is positive with respect to the lower terminal and adjustable terminal 57 is positive with respect to the lower terminal so that control grid 55 of tube VA is positive in potential with respect to cathode 49, the tube VA becomes conductive because anode 53 is now positive in potential with respect to cathode. With tube VA conductive relay 2ATR is picked up and it is retained picked up during the half cycles the tube is non-conductive due to its slow release characteristics. With relay 2ATR picked up closing front contact 33 an alternative path is closed for the anode circuit of tube VB and that tube is controlled as explained above. Accordingly, at this time the tubes VA and VB will be alternately rendered conductive by the full-wave alternating current energy which is supplied to the resistor R1 so that the grids 55 and 35 of tubes VA and VB, respectively, are alternately rendered positive with respect to their cathodes.

From the foregoing, it will be seen that with the train occupying section 3T and section 2T

unoccupied, the full-wave alternating current energy supplied over the rails 5 and 6 of section 2T to the apparatus located at the entrance end thereof causes the tubes VA and VB to be alternately conductive so that relays 2ATR and 2BTR are picked up. With the contacts of relay 2ATR and relay 2BTR picked, a circuit is established for supplying energy to the upper yellow lamp of signal 2S over front contact 59 of relay 2ATR,

10 while the lower red lamp 2BR of signal 2S is supplied with energy by a circuit including front contact 63 of relay 2BTR, so that at this time the signal 2S displays an aspect of yellow over red, denoting "approach next signal prepared to stop".

15 The relay 2CTR will be deenergized under this traffic condition since by examination of the circuits it will be noted that each time that the anode 43 of tube VC is positive with respect to its cathode, the energy supplied to the control grid 37

20 from the adjustable tap 25 of resistor R1 will be negative with respect to the cathode 39, so that the tube is prevented from conducting. During the alternate half cycles in which the anode 43 of tube VC is negative with respect to its cathode,

25 the control grid 37 will have a positive polarity with respect to the cathode but conduction cannot take place at this time since the anode 43 is now negative with respect to the cathode.

When the train vacates section 3T, the relays

30 3ATR and 3BTR will be picked up, as described in connection with the relays 2ATR and 2BTR associated with section 2T. Accordingly, at this time the energy supplied over the rails 5 and 6 of section 2T will be half-wave rectified energy

35 having a relative positive polarity, that is, energy will be supplied to the track rails during the half cycles in which the polarity is opposite to that indicated on the drawing. During these half cycles energy flows from the right-hand terminal of the

40 secondary winding of transformer 2TT, over front contact 9 of relay 3ATR, over front contact 11 of 3BTR, through the half-wave rectifier K1, over front contact 13 of relay 3BTR, over front contact 15 of relay 3ATR, over rail 5

45 to the upper terminal of load resistor R1, and from the lower terminal of resistor R1 over the rail 6 to the left-hand terminal of the secondary winding of transformer 2TT. It will be seen therefore that the energy supplied to resistor R1

50 at this time will consist of pulses of half-wave rectified energy having a polarity such that the upper terminal of resistor R1 is positive with respect to the lower terminal.

From an examination of the circuits, it will be 55 noted that during each pulse of the track circuit current the adjustable tap 57 of resistor R1 is positive with respect to the lower terminal of the resistor, and the polarity of the energy supplied to the anode 53 of tube VA is positive with respect to its cathode 49.

60 Since the adjustable tap 57 is positive with respect to the lower terminal of resistor R1, it will be seen that energy of positive polarity is supplied through the resistor R5 to the control grid 55 of tube VA, so that the tube 65 is rendered conductive on each pulse of positive half-wave rectified energy supplied over the track rails to resistor R1. As a result, the tube VA will fire on the recurrent half cycles of the energy supplied thereto, and as a result, the contacts of relay 2ATR will be picked up.

70 Also it will be seen that with the upper terminal of resistor R1 made positive with respect to the adjustable tap 25 by the track circuit pulses, the cathode 17 of tube VB will be positive with respect to the voltage supplied to its control grid 35

by way of the control grid 37 of tube VC and the adjustable tap 25. Accordingly, each time that the anode 21 of tube VB is positive with respect to its cathode 17, the control grid 35 will have a negative polarity with respect to the cathode, so that tube VB is prevented from conducting, and as a result, the relay 2BTR remains released.

Similarly, at this time the energy supplied from adjustable tap 25 of resistor R1 to the control grid 37 of tube VC is negative with respect to the cathode 39, so that the tube VC does not conduct and the contacts of relay 2CTR remain released.

With relay 2ATR picked up and the contacts of relay 2BTR released, a circuit is established for supplying energy to the upper yellow lamp 2AY of signal 2S over front contact 59 of relay 2ATR, and additionally, energy is supplied to the lower green lamp 2BG of signal 2S by a circuit including front contact 59 of relay 2ATR and back contact 71 of relay 2BTR, the contact 63 of relay 2ATR interrupting the supply of energy to the lower red lamp 2BR of signal 2S. It will be seen therefore, with sections 2T and 3T unoccupied and the section in advance of section 3T occupied, the signal 2S displays an aspect of yellow over green, denoting "approach next signal at medium speed."

When the train moving from left to right vacates the section beyond section 3T, relay 3ATR will be picked up, and relay 3BTR will be released, and the polarity of the half-wave rectified energy supplied to the rails of section 2T will be such as to have a relative negative polarity with respect to the rail 6. Under this traffic condition energy is supplied from the left-hand terminal of the secondary winding of transformer 2TT, over rail 6 of section 2T, to the lower terminal of resistor R1, through resistor R1 over rail 5 to the front contact 15 of relay 3ATR, over back contact 13 of relay 3BTR, through the half-wave rectifier K1, over front contact 65 of relay 3ATR, over back contact 11 of relay 3BTR, and over front contact 9 of relay 3ATR to the right-hand terminal of the secondary winding of transformer 2TT. Accordingly, it will be seen that under this traffic condition the pulses of half-wave rectified energy supplied over the section rails to the load resistor R1, are of what I have called negative polarity and as a result, the lower terminal of resistor R1 is positive with respect to the upper terminal.

The equipment at the entrance end of section 2T now operates in the manner as described originally, that is, under clear traffic conditions. The relay 2BTR will be energized due to the recurrent conduction of tube VB in response to the pulses of half-wave rectified energy supplied to its control grid, and relay 2CTR will be energized by the recurrent conduction of tube VC, so that relay 2BTR is picked up, and relay 2ATR is released, with the result that the signal 2S now displays its aspect of green over red, denoting "proceed."

When the train vacates the second section beyond section 2T, relay 3ATR will be released and relay 3BTR will be picked up. The equipment has now been restored to its normal condition previously described.

It will be seen from the foregoing, that the resistor R1 is included as a series element in the circuit for supplying energy to the shield grids of tube VA and tube VB. Accordingly, if the resistor R1 should become open circuited, the supply of energy to the shield grids of tube VA and tube VB would be interrupted, and as a result

energy would no longer be supplied through the transformers 2AT and 2BT to the anode circuits of the tubes VA and VB, with the result that relays 2ATR and 2BTR would release and remain released. Accordingly, the resistor R1 is checked to insure that it does not become open circuited since the resistor would have low enough resistance to take appreciable current from the track and thus provide broken rail protection and good shunting sensitivity under high ballast resistance conditions. If one of the section rails 5 or 6 becomes broken, or if the ballast resistance is sufficiently high, and resistor R1 becomes open, there will be insufficient current flow in the shield grid circuits for the tubes to supply sufficient energy to the secondary windings of the transformers 2AT and 2BT to pick up the relays 2ATR and 2BTR. If the rails 5 and 6 are intact and the ballast resistance between the rails is sufficiently low, then if resistor R1 becomes open, current through the primary windings of transformers 2AT and 2BT that by-passes R1 through ballast leakage may be of sufficient magnitude to cause the relays 2ATR and 2BTR to be picked up when the respective control tubes are rendered conductive, but there is no objection to permitting the relays to operate as usual under these circumstances.

The value of resistance normally required for R1 is so low that the voltage drops caused by the shield grid currents flowing in portions of R1 as described, are negligible compared with the voltage received from the track rails.

The tube VC and its associated relay 2CTR are provided to check against a possible clear signal failure in the condition where full-wave alternating current energy is applied to the exit end of section 2T, but relay 2ATR fails to pick up due to an open circuit or other derangement. It will be seen from the foregoing description and examination of the drawing that the anode 43 of tube VC is positive on the same half cycle as the anode 53 of tube VA, but its control grid will have a negative potential with respect to the cathode 39 if the track section 2T is energized on this half cycle. As a result, the tube VC will be rendered conductive and the associated relay 2CTR will be picked up when the negative half-wave rectified impulses are present in the track section 2T, but will not be conductive when the full-wave alternating current energy is present in the section 2T or when the half-wave rectified energy has a positive polarity. Accordingly, if the full-wave alternating current energy is being supplied to the rails 5 and 6 of section 2T, but the relay 2ATR fails to pick up due to a broken wire or other derangement of this circuit, the relay 2CTR will also be deenergized at this time, and as a result the circuit for relay 2BTR is interrupted by the front contact 31 of relay 2CTR and front contact 33 of 2ATR so that relay 2BTR remains released. With relays 2ATR and 2BTR released, the signal 2S will display an aspect of red over red, denoting "stop."

Also, it will be seen that with the circuits for supplying energy to the exit end of section 2T arranged in the manner shown, the failure of rectifier K1 can only cause a more restrictive indication to be displayed by the signal 2S than would otherwise be displayed if the rectifier were intact and operating properly. For example, should the traffic conditions in and ahead of section 3T be such that the apparatus at the exit end of section 2T is conditioned to supply 75 pulses of half-wave rectified energy having a

negative polarity to these section rails, as shown in the drawing, and the rectifier K1 should become short-circuited, it will be seen that full-wave alternating current energy will then be supplied to the section rails 5 and 6 of section 2T. Accordingly, the relays 2ATR and 2BTR will be picked up, and their contacts will establish the circuit previously described for supplying energy to the upper yellow lamp 2AY of signal 2S and the lower red lamp 2BR of signal 2S so that the signal displays an aspect of yellow over red denoting "approach next signal prepared to stop." If the rectifier K1 should become open-circuited, no energy will be supplied to the section rails 5 and 6 and the relays 2ATR and 2BTR will be released, so that the signal 2S displays a red aspect, denoting "stop."

Although I have herein shown and described only one form of electron tube circuits embodying my invention, it is to be understood that various changes and modifications may be made therein within the scope of the appended claims without departing from the spirit and scope of my invention.

Having thus described my invention, what I claim is:

1. In combination, a first, and a second electron tube circuit, each comprising an electron tube having at least an anode, a cathode and a control electrode and having a winding of a relay in series with its anode, whereby the relay is energized when the tube is rendered conductive by the application of control voltage to the control electrode of the tube, a coupling impedance, said control electrodes being connected to said coupling impedance, so that the voltage drop across said coupling impedance caused by the flow of current therethrough is impressed on said control electrodes and said control electrodes being connected to said coupling impedance so that the polarity of the energy supplied from said coupling impedance to the control electrode of said first tube is opposite in polarity to the energy supplied from said coupling impedance to the control electrode of said second tube, means for at times supplying unidirectional pulses of current of one polarity or the other to said coupling impedance, means for at other times supplying alternating current energy to said coupling impedance, a circuit governed by contacts of said first and second relays, and means for checking the response of said first and second tubes to alternating current energy supplied to the control electrodes of said tubes, said last named means comprising a third electron tube having a relay in its anode circuit and arranged to become conductive when energy is supplied thereto from said coupling impedance which is effective to cause said second tube to become conductive and arranged to be non-conductive when energy is supplied thereto from said coupling impedance which is effective to cause said first tube to become conductive.

2. In combination, a first, a second and a third electron tube each having an anode, a cathode and a control electrode; a relay for each of said tubes, a source of alternating current, a load circuit including a coupling impedance, supply means including a rectifier and operable to different positions to connect said source to said load circuit to supply rectified current of negative or positive polarity or alternating current to the load circuit according to the position of the supply means, a power transformer receiving energy from said source, an anode circuit for

each of said tubes having connections to the anode and cathode of the tube and including a secondary winding of said transformer and a winding of the respective relay, said control electrodes connected to terminals of said coupling impedance so that the voltage applied to the control electrode of said first tube is opposite in phase to the voltage applied to the control electrodes of said second and third tubes, said tubes connected in a manner for said first tube to be conductive to energize its relay in response to rectified current of positive polarity supplied to the load circuit for said second tube to be conductive to energize its relay in response to rectified current of negative polarity supplied to said load circuit and said third tube to be made conductive to energize its relay during the half cycle of the alternating current source when no current is supplied to the load circuit when rectified current of negative polarity is supplied thereto, two alternate paths one including a front contact of the relay of said first tube and one including a front contact of the relay of said third tube interposed in the anode circuit of said second tube, and circuits selectively controlled by said relays of said first and second tubes.

3. In combination, a first and a second electron tube each having an anode, a cathode and at least one control electrode; a source of alternating current, a load circuit including a load resistor, supply means including a rectifier and operable to different positions to connect said source to the load circuit to supply rectified current of one relative polarity or rectified current of the other relative polarity or full-wave alternating current according to the position of the supply means, a power transformer receiving power from said source, a relay for each of said tubes, an anode-cathode circuit means for each of said tubes having connections to the anode and cathode of the respective tube and including a secondary winding of said transformer and a winding of the respective relay, a control circuit for each of said tubes having connections to the control electrode and cathode of the respective tube and to a selected terminal of said load resistor, said control circuits disposed for said first tube to be conductive to energize its relay when rectified current of said one relative polarity is supplied to the load circuit and for said second tube to be conductive to energize its relay when rectified current of said other relative polarity is supplied to said load circuit and for both tubes to be conductive and both relays energized when alternating current is supplied to said load circuit, a controlled device operable to different positions and selectively controlled through contacts of the relays of said first and second tubes, a checking electron tube and relay, said checking tube having an anode, a cathode and a control electrode and provided with an anode-cathode circuit connected to the anode and cathode of the tube and including a secondary winding of said transformer and a winding of said checking relay, said checking tube also provided with a control circuit connected to its control electrode and to said load resistor and disposed to permit the checking tube to be conductive to energize the checking relay when rectified current of said other relative polarity is supplied to the load circuit, but not when rectified current of said one relative polarity or alternating current is supplied to the load circuit, and a front contact of said checking

relay and a front contact of the relay of said first tube interposed in multiple in the anode-cathode circuit of said second tube.

4. In combination, a first and a second electron tube each having an anode, a cathode and at least one control electrode; a source of alternating current, a load circuit including a load resistor, supply means including a rectifier and operable to different positions to connect the load circuit to said source to supply rectified current of one relative polarity or rectified current of the other relative polarity or full-wave alternating current according to the position of the supply means, a power transformer receiving power from said source, a relay for each of said tubes, an anode-cathode circuit means for each of said tubes having connections to the anode and cathode of the respective tube and including a secondary winding of said transformer and a winding of the respective relay, a control circuit for the two tubes and having connections to the control electrodes and cathodes of the tubes and to a terminal of said load resistor, said two anode-cathode circuit means and said control circuit provided with connections for said first tube to be made conductive and its relay energized in response to rectified current of said one relative polarity supplied to said load circuit due to a given position of the supply means and for said second tube to be made conductive and its relay energized during the half cycle of the alternating current no current is supplied to the load circuit for said given position of the supply means, and a front contact of the relay of said second tube interposed in the anode-cathode circuit means of said first tube.

5. In combination, two electron tubes each having an anode, a cathode and a control elec-

trode; a relay for each of said tubes, a source of alternating current, a transformer receiving energy from said source, an anode-cathode circuit means for each of said tubes having connections to the anode and cathode of the tube and including a secondary winding of said transformer and a winding of the respective relay; a load resistor, means operable during a given time to supply to said load resistor from said source rectified current of a given polarity, a control circuit for the two tubes having connections to the cathodes of the tubes in multiple and to the control electrodes of the tubes in series and to said load resistor, said control circuit and said anode-cathode circuit means poled for a first one of said tubes to be conductive and energize its relay in response to said rectified current supplied to said load resistor and for a second one of said tubes to be conductive to energize its relay in response to the half cycle of the alternating current from said transformers that current is not supplied to said resistor during said given time, and a front contact of the relay of said second tube interposed in the anode-cathode circuit means of said first tube.
